ROOF LAYING SCAFFOLD

Hans H. Doe, Milwaukee, Wis., assignor to Copper
Roofs Corporation, Milwaukee, Wis., a corpo-
ration of Michigan

Application July 20, 1936, Serial No. 91,557

8 Claims. (Cl. 304—20)

The invention relates to scaffolding and more particularly to a scaffolding for the laying of roofs or roof covering material.

The object of the invention is to provide a scaffolding of light weight construction which may be easily carried from one job to another and quickly placed in position on a roof and shifted to different positions on the roof when desired. More particularly, the invention comprises two or more platform supporting units which are formed as ladder-like structures that are adapted to be supported on edge above the roof so as to take boards between them to form a platform above the roof surface to support the operator or operators laying the roofing material.

A further object of the invention is to provide a scaffolding unit in the form of a ladder having diagonally disposed platform receiving rungs and which ladder may comprise one or more sections to accommodate different widths of roof.

The invention further consists in the several features hereinafter set forth and more particularly defined by claims at the conclusion hereof.

In the drawings:

Fig. 1 is an end view of a roof with the scaffolding embodying the invention mounted thereon;

Fig. 2 is a plan view of a scaffolding embodying the invention;

Fig. 3 is a detail elevation view of one of the scaffolding units, parts being broken away;

Fig. 4 is a detail sectional view taken on the line 4—4 of Fig. 1;

Fig. 5 is a detail sectional view taken on the line 5—5 of Fig. 4;

Fig. 6 is a detail sectional view taken on the line 6—6 of Fig. 3;

Fig. 7 is a detail sectional view taken on the line 7—7 of Fig. 3.

Referring to the drawings, the scaffolding embodying the invention includes two or more platform supporting units 10.

Each of the units 10 may comprise one or more sections 11 and each section 11 is a ladder-like structure having stays 12 and rungs 13 connecting said stays and in addition rungs 14 extending diagonally between the stays and the rungs 13.

Where these units are formed of a plurality of sections, adjacent sections are joined together to form an extended unit by tubular extensions 15 secured to one of the sections and into which the ends 16 of the adjacent section telescope, and in order to hold these jointed parts securely together releasable ties may be provided connecting adjacent rungs of adjacent sections together. These ties are here shown as formed

by a band metal member 17 pivotally anchored at one end to one of the rungs and a releasable hook 18 connected at one end to the free end of the band member 17 and adapted to engage the other rung to be connected and when so engaged be locked in position by a clip or ring 19 slidably mounted on the member 17 and adapted to be slipped over the free end of the hook 18 as shown more particularly in Fig. 7.

Each scaffolding unit is adapted to be supported on edge above the roof, and for this purpose two or more supports 20 are provided. Each of these supports has a supporting foot member 21, an upright member 22, and diagonal brace members 23 and 24, these parts preferably being formed of angle iron pieces riveted or welded together. The foot member 21 may have holes for receiving nails 25 or other temporary fastening means for securing it to the roof, it being noted, however, that for each scaffolding unit only one of its supports need be nailed to the roof during operation, and this is usually the upper support. The uprights 22 each have spaced hooks 26 secured thereto at one side, and each of these hooks cooperates with the uprights to form stay receiving pockets in which the stays are mounted at any desired position along their length as shown in Fig. 4. In addition to prevent any shifting of the unit relative to its support, each support has a lengthwise extending rung receiving hook 27 adapted to engage one of the rungs 13.

Thus the brackets or supports 20 support the units 10 on edge above and parallel to the roof, and with most roofs this places the rungs 14 either in horizontal plane or approaching such a plane so that boards 28 may be laid at their ends on aligned diagonally disposed rungs 14 and thus form a working platform for the operator or operators engaged in laying or removing the roofing material on or from the roof. While three units are shown in Fig. 2, it will be understood that two units may be used where the space between them is sufficient to carry one platform member the length of a roof but that for longer roofs more units will be necessary.

The sections 11 are here shown as formed of metal parts, the stays being hollow metal squares, and the rungs metal tubes welded at their ends to the stays.

Where the roof is very steep, the rungs 13 may be used as the platform supports.

I desire it to be understood that this invention is not to be limited to any particular form or

arrangement of parts except insofar as such limitations are included in the claims.

What I claim as my invention is:

1. In a device of the character described, a platform carrying structure comprising a ladder-like unit having spaced stays and platform receiving rungs, and means for mounting said unit on edge above the roof.
2. In a device of the character described, a platform carrying structure comprising a pair of spaced stays, and diagonally disposed platform receiving rungs extending between and connected to said stays, and means for supporting said structure on edge above the roof.
3. In a device of the character described, a platform carrying structure comprising a pair of spaced stays, rungs connecting said stays and extending at substantially right angles thereto, and platform receiving rungs extending between said stays at an angle less than a right angle, and means for supporting said structure on edge above the roof.
4. In a device of the character described, a platform carrying structure comprising a pair of spaced stays, rungs connecting said stays and extending at substantially right angles thereto, and platform receiving rungs extending diagonally between said stays and first named rungs, and means for supporting said structure on edge above the roof.
5. In a device of the character described, a platform carrying structure comprising a ladder-

like unit having spaced stays and rungs, a support for said unit comprising a base, an upright, and means on said upright for fastening the stays thereto in vertically spaced position.

6. In a device of the character described, a platform carrying structure comprising a ladder-like unit having stays and rungs, a support for said unit comprising a base and an upright on which said unit is mounted on edge above the roof, said upright provided with stay engaging hooks and a rung engaging hook.

7. In a scaffolding structure, the combination of a plurality of spaced platform receiving units, said units being formed of ladder-like sections having telescopically jointed connections, and means for tying together the sections at said joints, and supports for said units supporting the same on edge above the roof.

8. In a device of the character described, a platform carrying structure comprising sections, each section having a pair of spaced stays and platform supporting rungs extending therebetween, a telescoping joint between adjacent sections, means for connecting adjacent sections together comprising a releasable hook engaging a rung of one section and a tie member connecting said hook with a rung of the adjacent section, and means for supporting the joined together sections in a plane passing through the stays and substantially normal to the roof.
